UNITED STATES PATENT OFFICE.

JOHN ROGERS, OF NEW CANAAN, CONNECTICUT.

DESIGN FOR A GROUP OF STATUARY.

SPECIFICATION forming part of Design No. 16,836, dated August 3, 1886.

Application filed June 14, 1886. Serial No. 205,150. Term of patent 14 years.

To all whom it may concern:

Be it known that I, JOHN ROGERS, a citizen of the United States, residing at New Canaan, in the county of Fairfield and State of Connecticut, have invented and produced a new and original Design for a Group of Statuary, of which the following is a specification, reference being had to the accompanying photograph, forming part thereof.

10 The group consists of three figures—Romeo, Juliet, and the nurse, in representation of the line in Shakespeare's play, Act I, Scene 5, where the nurse says "Madam, your mother craves a word with you." This quotation is marked on the base. The figures are all standing. Juliet is the central one. A veil hangs from her head over each shoulder. She has on a close-fitting dress. A small bag is suspended from a girdle round her waist, and by

I claim—

20 The design for a group of statuary herein shown and described, representing Romeo, 30 Juliet, and the nurse, in illustration of the line in Shakespeare's play where the nurse says "Madam, your mother craves a word with you."

JOHN ROGERS.
